UNITED STATES PATENT OFFICE

WILLIAM H. KING, OF CLINTON, MASSACHUSETTS, ASSIGNOR TO CROMPTON & KNOWLES LOOM WORKS, OF WORCESTER, MASSACHUSETTS, A CORPORATION OF MASSACHUSETTS

REVOKER FOR WEFT-REPLENISHING LOOMS

Application filed March 1, 1929. Serial No. 343,690.

This invention relates to improvements in weft replenishing looms of the type having regularly moving transerrer arms and it is the general object of the invention to prevent a transerrer in such a loom when the shuttle is widely misplaced.

In Patent No. 1,372,316 there is shown a weft replenishing mechanism having a weft detector mounted on a transerrer arm which moves downwardly on alternate beats of the loom to detect the condition of weft when the active shuttle is on the magazine end of the loom. The downward movement of the transerrer arm is caused by a cam operating through a reciprocating rod, the cam being preferably located on the bottom shaft of the loom and turning whenever the loom is in operation.

It occasionally happens that the shuttle will not be properly boxed when transfer is about to take place and as a result a bobbin is likely to be broken. It is an important object of my present invention to interpose between the reciprocating rod and the transerrer arm a form of connection which may be interrupted whenever the shuttle is improperly placed so as to prevent descent of the transerrer arm.

With these and other objects in view which will appear as the description proceeds, my invention resides in the combination and arrangement of parts hereinafter described and set forth in the claims.

In the accompanying drawings wherein a convenient embodiment of my invention is set forth,

Fig. 1 is a top plan view of a portion of a loom having my invention applied thereto;

Fig. 2 is an end elevation looking in the direction of arrow 2, Fig. 1;

Fig. 3 is an enlarged horizontal section on line 3—3 of Fig. 2;

Fig. 4 is a section on line 4—4 of Fig. 1 on an enlarged scale, and

Fig. 5 is a detailed vertical section on line 5—5 of Fig. 1.

Referring to Figs. 1 and 2, I have shown a loom frame 10 and a lay 11, the latter being provided with a shuttle S carrying yarn to be detected and replenished. A stand 12 is secured to the frame 10 and has secured therein a hollow stud 13 held in position by a set screw 14. A transerrer arm 15 is provided with a hub 16 which is mounted for free rotation on the right hand end of said stud 13 as shown more particularly in Fig. 3. The transerrer arm extends rearwardly and has an extension 17 which lies over the shuttle S, said extension being provided with a form of detector indicated herein generally at D.

The rod 18 is operated by mechanism not shown herein but set forth in prior patent to Ryon, No. 1,372,316, said rod being given a quick downward movement when the shuttle S is on the magazine side of the loom so as to present the detector D to the yarn in the shuttle. The detector and also the function of the transerrer arm under normal conditions is substantially the same as set forth in said patent to Ryon.

There is secured to the loom frame 10 the base 20 of a combined shuttle feeler and filling stop motion, said base having spaced vertical walls 21 between which slide a carrier 22 having mounted on the rear end thereof a shuttle positioning roll 23. A plunger 24 has the rear end in engagement with the carrier and the forward end extends through a stationary guide 25. A coil spring 26 is interposed between a rear part of the carrier and the fixed guide and serves to hold the carrier yieldingly in rearward position.

Under normal conditions when the shuttle is properly boxed the inner end thereof will clear the roll 23, but if the shuttle be slightly misplaced said roll will engage the rounded end of the shuttle and serve to push the latter into the box, the compression spring 26 being strong enough to accomplish this result.

If, on the other hand, the shuttle be so widely misplaced that the roll engages a portion of the shuttle which is substantially parallel to the reed the carrier will move forwardly 5 as a whole against the action of the spring 26. The shuttle placer and its manner of operation is substantially the same as that shown in prior patent to Ryon, No. 1,549,221, to which reference may be had for a more 10 complete understanding of the operation of the shuttle placer and revoker. As shown in said later patent to Ryon forward movement of the carrier is effective to stop the loom, but this feature is not carried into my 15 present construction, as I make use of the forward movement of the carrier to act as a revoker to prevent operation of the trans- ferrer lever 15.

The stand 12 is part of a magazine indicated generally at M, said magazine being 20 provided with a forward stationary bobbin support 30 and a rear yielding bobbin support 31. These supports are so located that they will hold a bobbin in transfer position as indicated in dot and dash lines in Fig. 2. The magazine may be substantially the same as set forth in the first named Ryon patent and it is not believed necessary to show herein 25 how the bobbin B arrives in the position shown in Fig. 2. It is sufficient for the purposes of my present invention to state that the bobbin which is to be inserted in the depleted shuttle will move to the position shown 30 in Fig. 2 while the transerrer arm 15 is elevated and will be so placed as to be moved by the latter into the depleted shuttle.

A releasing lever 32 may be pivoted as at 33 to a fixed part of the magazine and engages a cam surface 34 formed on part of the 40 movable support 31. By means of a rod 35 which may be connected to any regularly moving part of the loom, such as the picking motion, the lever 32 may be given an operative movement to draw the support 31 rearwardly at regular intervals, preferably 45 on the first backward stroke of the lay after a detecting movement on the part of the transerrer arm. The mechanism for moving the support 31 rearwardly is substantially similar 50 in operation and function to the structure shown in prior patent to Gordon, No. 932,119.

The matter thus far described may be as set forth in the previously named patents and forms no part of my present invention.

In carrying my invention into effect I provide mechanism operable by the slide or carrier 22 to disrupt the normal connection between the rod 18 and the transerrer arm 15. 60 In carrying my invention into effect I pivot an actuator lever 40 to the transerrer arm by means of a stud 41. If desired said stud may project beyond the transerrer arm to the left as shown in Fig. 4 and have there- 65 around a compression spring 42 which lies

between the head 43 of the stud and the transerrer lever. The spring normally holds the nut 44 on the right end of the stud against the actuator lever 40. A control plunger 45 extends through the holder stud 13 and enters a hole 46 formed in the forward end of the actuator lever. Said plunger is concentric with the axis of the transerrer lever so that when the plunger is in the hole 46 as shown in Fig. 3 vertical reciprocations 75 of the rod 18 will be communicated to the transerrer lever by means of the actuator lever.

An arm 50 is secured to the left hand end of the plunger 45 as shown in Fig. 3 and has 80 a pin 51 which receives one end of a tension spring 52 the other end of which is fixed with respect to the stand 12 by means of a second pin 53. The function of the spring 52 is to hold the rod or plunger 45 in the 85 opening 46. A vertical stud 54 is secured to the stand 12 and affords pivotal support for the hub of a lever 55 one arm 56 of which is forked as shown in Fig. 5 to surround the plunger 45 and also to extend into engaging 90 position with the arm 50. Said lever 55 is provided with a second arm 57 positioned for engagement with the upstanding finger 58 of an adjustable trip 59. The trip is provided with a slot 60 to permit adjustment 95 of the same with respect to the carrier 22 and is held to the latter by means of a screw 61. A stop pin 62 extending upwardly from the stand 12 engages the arm 57 to limit movement of the same in a right hand direction 100 around stud 54 under influence of spring 52.

Under normal conditions when the shuttle is being boxed properly the carrier 22 will remain at rest and the spring 52 will act through the arm 50 to hold the right hand end of the plunger 45 as viewed in Figs. 1 and 3 in the opening 46 in the actuator lever 40. Because of the fact that the plunger 45 is concentric with the axis of the transerrer arm the latter together with the actuator lever is free to move about the axis of the transerrer arm under influence of the reciprocating rod 18. The plunger, actuator lever and transerrer lever and also the rod 18 remain related as shown in full lines in Fig. 2 so long as the carrier remains at rest and in rearward position. Should the shuttle be misplaced when on the magazine end of the loom, during the forward beat of the lay end, but so far out of the box as not to be placed by the roll 23, the carrier 22 will move forwardly to cause the finger 58 of the trip 59 to engage the arm 57 and move the same in a counter-clockwise direction around stud 54 to the dotted line position shown in Fig. 3. This movement is accompanied by a movement to the left on the part of the forked arm 56, thereby causing the arm 50 and stud to move to the left of the dotted line position shown in Fig. 3. The plunger 130

45 is thereupon withdrawn from the opening 46 and the rod 18 in descending will cause 5 rocking movement of the actuator lever 40 with respect to the transferrer arm to cause said actuator lever to assume the dotted line position shown in Fig. 2.

In order to prevent downward movement 10 of the transferrer lever which remains unsupported when the plunger 45 is withdrawn from the opening 46, I provide the hub 16 with a forward projection 70 through which extends rod 71 surrounded by a spring 72 which is interposed between the projection 70 and a fixed lug 73. Said spring is sufficiently long to permit a complete downward 15 movement of the transferrer arm under normal conditions, but acts to hold the transferrer arm raised when the plunger is withdrawn from holding engagement with the actuator lever 40.

The rod 18 will therefore be free to move 20 downwardly under action of the cam not shown without causing descent on the part of the transferrer lever. The detector D will 25 consequently be held out of engagement with any portion of the shuttle which might damage it due to the fact that the shuttle is misplaced, and if a bobbin is in transfer position it will not be forced against a misplaced 30 shuttle.

As the lay moves backwardly it will carry the misplaced shuttle with it and the spring 26 will move the carrier 22 rearwardly, thereby relieving the forked arm 56, freeing spring 35 52 so that the latter may tend to move the plunger 45 toward the actuator lever. At a later time in the cycle of the loom the rod 18 will be raised and during this upward movement the left hand end of the actuator 40 lever as viewed in Fig. 2 will be moved so as to bring the opening 46 opposite the plunger 45, whereupon spring 52 will urge said plunger into the opening, thus reestablishing normal relations between the parts.

If a bobbin remains untransferred because 45 of the previously described operation of the carrier it will be relieved before the transferrer arm moves down on a normal beat of the loom through the action of the releasing lever 32. This result is particularly desirable 50 on multicolor looms where a mixing of the colors would otherwise result, but it is not considered essential in single color work.

From the foregoing it will be seen that I 55 have provided means associated with the transferrer arm for preventing downward movement of the latter when the shuttle is misplaced. It will also be seen that after the operating parts are disconnected they 60 will automatically be restored at a subsequent point in the cycle of operation of the rod 18.

Having thus described my invention it will 65 be apparent that changes and modifications may be made therein by those skilled in the

art without departing from the spirit and scope of the invention and I do not wish to be limited to the details herein disclosed, but what I claim is:

1. In a weft replenishing loom, a regularly moving actuator, a transferrer arm, a lever pivoted on the transferrer arm and normally operatively connected to the actuator, means to cause said lever and transferrer arm to move together normally to cause the actuator to move the transferrer arm regularly, and mechanism operated by a misplaced shuttle to move said means so that the latter is ineffective to cause the transferrer arm and said lever to move together so that said actuator moves without causing motion of the transferrer arm. 70

2. In a weft replenishing loom, a regularly moving actuator, a transferrer arm, a pivot around which said transferrer arm is movable angularly, a lever pivoted to the transferrer arm and operatively connected to the actuator, means extending coaxially with the pivot to engage the lever normally and define an axis around which said lever moves to cause said transferrer arm and lever to move together normally under influence of the actuator, and mechanism operable by a misplaced shuttle to move said means out of engagement with the lever, whereby the latter is movable with the actuator without causing movement of the transferrer arm. 85

3. In a weft replenishing loom, a regularly moving actuator, a transferrer arm, a pivot around which said transferrer arm is movable angularly, a lever pivoted to the transferrer arm and operatively connected to the actuator, a plunger slidable axially with respect to the pivot for the transferrer arm and normally serving as the pivot around which the lever moves, the lever and arm normally moving in unison, and mechanism operated by a misplaced shuttle to withdraw said plunger from its normal pivoting position with respect to the lever, whereby said lever moves with the actuator as the latter has a normal movement without causing motion of the transferrer arm. 100

4. In a weft replenishing loom, an actuator having a regular movement, a transferrer arm to be moved by the actuator, means defining a pivot around which the transferrer arm moves angularly, a lever pivotally connected to the transferrer arm at a point eccentric with respect to the axis of the transferrer arm and operatively connected to the actuator, an auxiliary pivot element coaxial with the pivot of the transferrer arm and normally operatively related to the lever to act as a pivot around which the latter moves under normal conditions, and mechanism operated by a misplaced shuttle to withdraw the auxiliary pivot from operative relation with respect to the lever, thereby disconnecting the operative connection between the 115 120 125 130

transferrer arm and the lever so that as said actuator moves normally the transferrer arm will remain at rest.

5. In a weft replenishing loom, a regularly moving actuator, a transferrer arm to be operatively connected to the actuator to move normally with the latter regularly as the loom operates, a lever pivotally mounted on the transferrer arm and normally operatively connected to the actuator, means engaging the lever at a point other than its pivotal connection with the transferrer arm to cause

10 said lever and arm normally to move regularly in unison, and mechanism actuated by a misplaced shuttle to move said means out of normal relation with respect to the lever so that the latter moves pivotally with respect to the transferrer arm under influence of the actuator while the transferrer arm is at rest.

15 6. In a weft replenishing loom, a regularly moving actuator, a pair of pivotally connected members one of which is operatively related at all times to the actuator and the other of which is effective to cause a transfer of bobbins, means normally requiring said members to move in unison so that normally the actuator causes regular periodic movements of the member which effects 20 transfer of bobbins, and mechanism effective when the shuttle is misplaced to move the means so that said members are movable with respect to each other; said member to effect transfer remaining at rest while the actuator 25 and other member move.

30 7. In a weft replenishing mechanism, a regularly moving actuator, a pair of members normally connected together at two spaced points, one of said members effective 35 to cause a transfer of bobbins and the other member operatively connected to the actuator, and means effective when the shuttle is misplaced to disconnect said members at one of the aforesaid points so that the member to effect transfer remains at rest while the other member and the actuator move.

40 8. In a weft replenishing mechanism a regularly moving actuator, a pair of members, a pivotal connection between said members, a second pivot about which both of said members normally move, one of said members effective to cause transfer of bobbins in the replenishing mechanism and the other member being operatively connected to the 45 actuator, and means effective when a shuttle is misplaced and the actuator has its normal movement to disconnect one of said members from the second pivot so that said actuator has a regular movement while the member to effect transfer remains at rest.

50 9. In a weft replenishing mechanism, an upright rod having regularly recurring reciprocating movements, a lever operatively connected to said rod, a transferrer arm pivotally connected to the lever, a hollow fixed

55 member serving as a pivot around which the transferrer arm is angularly movable, an element movable through the hollow member and normally engaging the lever at a point spaced from the pivotal connection between said lever and transferrer arm to cause the transferrer arm to move with the rod, and means operated by a misplaced shuttle to withdraw said rod from operative connection with the lever, whereby said lever and rod move with respect to the transferrer arm while the latter remains substantially at rest.

60 10. In a weft replenishing mechanism, an upright rod having regularly recurring reciprocating movements, a lever operatively connected to said rod, a transferrer arm pivotally connected to the lever, a hollow fixed member serving as a pivot around which the transferrer arm is angularly movable, an element movable through the hollow member and normally engaging the lever at a point spaced from the pivotal connection between said lever and transferrer arm to cause the transferrer arm to move with the rod, means operated by a misplaced shuttle to withdraw said rod from operative connection with the lever, whereby said lever and rod move with respect to the transferrer arm while the latter remains substantially at rest, and means to limit downward movement of the transferrer arm when the latter is disconnected from the lever.

65 11. In a weft replenishing mechanism, an actuator having regular movements in opposite directions, a pair of members one of which is effective to cause a transfer of bobbins in the mechanism and the other of which is operatively connected to the actuator, a pivotal connection between said members, a second pivot spaced from said pivotal connection and around which the members normally move, said second pivot being in two parts, one movable with respect to the other and having operative engagement with the member operatively connected to the actuator, and means operative when a shuttle is misplaced to move the parts of the second pivot with respect to each other so that the member operatively connected to the actuator is disconnected from the second pivot

70 100 and moves with the actuator relatively to the transferrer arm while the latter remains substantially at rest.

75 115 12. In a weft replenishing mechanism, an actuator having regular movements in opposite directions, a pair of members one of which is effective to cause a transfer of bobbins in the mechanism and the other of which is operatively connected to the actuator, a pivotal connection between said members, a second pivot spaced from said pivotal connection and around which the members normally move, said second pivot being in two parts, one movable with respect to the other and having operative engagement with the

member operatively connected to the actuator, means operative when a shuttle is misplaced to move the parts of the second pivot with respect to each other so that the member operatively connected to the actuator is disconnected from the second pivot and moves with the actuator relatively to the transerrer arm while the latter remains substantially at rest, and means to limit downward movement of the transerrer arm.

13. In a weft replenishing mechanism, a regularly moving actuator, a pair of members capable of relative movement with respect to each other under abnormal conditions but normally moving in unison, one of said members effective to cause a transfer of bobbins and the other member operatively connected to the actuator, means normally requiring said members to move together under influence of the actuator without relative movement with respect to each other, and mechanism effective when the shuttle is misplaced to move said means to release one of said members so that the same may move with the actuator while the member to effect transfer of bobbins remains substantially at rest.

14. In a weft replenishing mechanism, an actuator having a regularly recurring movement, a pair of members capable of relative movement with respect to each other under abnormal conditions but normally moving in unison, a pivot defined by two coaxial elements, one of said elements constituting the pivot around which one of said members moves and the other element constituting the center around which the other member moves, said members under normal conditions moving around said coaxial elements under influence of the actuator, and means to move said elements with respect to each other so that one of said members is without a pivotal connection with respect to either element when the shuttle is misplaced, said members under these conditions moving with respect to each other, the member to effect transfer remaining substantially at rest while the other member moves with the actuator.

15. In a weft replenishing mechanism, an actuator having a regularly recurring movement, a pair of members capable of relative movement with respect to each other under abnormal conditions but normally moving in unison, a pivot defined by two coaxial elements, one of said elements constituting the pivot around which one of said members moves and the other element constituting the center around which the other member moves, said members under normal conditions moving around said coaxial elements under influence of the actuator, means to move said elements with respect to each other so that one of said members is without a pivotal connection with respect to either element

when the shuttle is misplaced, said members under these conditions moving with respect to each other, the member to effect transfer remaining substantially at rest while the other member moves with the actuator, and yielding means tending normally to move the element for the member operatively connected to the actuator into pivotal relation with respect to the last named member.

In testimony whereof I have hereunto affixed my signature.
